UNITED STATES PATENT OFFICE.

LESLIE M. PAGE, OF MAPLEWOOD, NEW JERSEY, AND LOUIS MEYLACH, OF BROOKLYN,
NEW YORK.

WEB FEED FOR PRINTING PRESSES.

Application filed June 5, 1926. Serial No. 113,855.

This invention relates to web-feed for printing presses and has for its object to provide a device of the class specified, simple in construction and reliable in operation.

- 5 To these and other objects which will be more specifically pointed out herein, our improvements comprise features illustrated in their preferred embodiment in the drawings accompanying this specification, wherein:
- 10 Figure 1 is a side elevation, with the front frame removed, of so much of a known type of bed and platen printing press as will suffice to show the application of our improvements thereto. Fig. 2 is a plan corresponding with the showing of Fig. 1. The scale of the two figures is the same.

While our improvements are shown herein as applied to a two-station printing press, such as is described and claimed in U. S. 20 Letters Patent No. 1,494,702, granted May 20, 1924, to the present applicants, it will be obvious to those skilled in the art that said improvements are applicable to any single station bed and platen press of the 25 same general type. In such case carriage 10 and platen 5 are considered integral.

Forms 2 and 3 are removably fixed on bed 4 and platen 5 is mounted for oscillation on shaft 6 having bearings in opposite side frames 7 and 8. Said platen is oscillated toward and from forms 2, 3, by known means, not shown, through link 9. Carriage 10 is mounted for transverse reciprocation on platen 5 and is retained thereon by gib 35 11, 12. To the rear end of carriage 10 is fixed cam 13 for engagement with suitable carriage shifting means not shown herein, but which is fully shown in the above mentioned Patent No. 1,494,702, to which reference may be had.

For supporting roll 40 of web material 23, box 41 depends from gib 11 of carriage 10. Pivoted at 14, near the lower edge of carriage 10, is a modified form 15 of the usual sheet gripper. In the present case, for convenience, said gripper is reversed U-shaped, its upper transverse arm having web 23 passing thereover and the arms of said gripper are adjustably fixed to axial bar 16 by screws 45 17, 18. The lower ends of said gripper arms

are connected by cross-bar 19, to which is adjustably fixed by thumb screws 20, 21, clamp 22 for applying tension to web 23 thereunder. Leaf spring 24 is interposed between screws 20, 21 and clamp 22.

For lifting gripper 15 at suitable times, arm 25 fixed to pivot shaft 14 has pin 26 fixed in its lower end for engagement with cam 27 fixed to frame 7. Strap 28 is fixed by suitable screws to platen carriage 10 near the lower left hand end of said carriage and under which strap web 23 freely passes.

Web tension and winding means are carried by said carriage at its upper right hand end on brackets 29, 30 fixed by screws 32, 32 65 respectively to carriage cam 13. Between said brackets 29, 30 web tension rods 33 to 37 are mounted and said rods may be provided with collars as 38 for guiding the web transversely. Said web is reeled onto shaft 42 by the following means: Said shaft turns freely in bearing 43 of bracket 29 and is prevented from anti-clockwise rotation by pawl 44 in spring pressed engagement with ratchet 45 fixed to shaft 42. Turning freely on said shaft 42 between bearing 43 and friction disc 46 is gear 47. Said friction disc is slidably keyed to shaft 42 and is urged against gear 47 by spring 48. Small electric motor 49 is carried by bracket 29 and through suitable 70 75 reducing gearing drives gear 47.

As described herein carriage 10 is shiftable transversely of platen 5 to coact successively with two forms on bed 4 and pin 26 of gripper 15 therefore engages cam 27 85 at alternate backward movements of platen 5 whereby two impressions are had on web 23 for each incremental feed thereof.

The operation of the device is as follows: When platen 5 swings back from engagement with form 2 on bed 4, pin 26 engages cam 27, whereby gripper 15 is lifted from the face of carriage 10 on said platen, lifting web 23 therewith, withdrawing the necessary web portion from roll 40 to that end, the tension pins 33 to 37 and friction on shaft 42 holding the windup portion of the web against the pull of gripper 15. Then, on the forward movement of platen 5 gripper 15 descends onto carriage 10 and the slack of web 23 is 90 95 100

taken up by the friction driven winding means and said slack is wound onto shaft 42.

By shifting gripper 15 to bring its transverse arm 50, nearer to or farther from axial bar 16, less or greater increments of web may be fed to printing position.

We claim:

1. In a web feed for printing presses the combination of an oscillating platen, a gripper pivotally mounted at the lower end of said platen, a transverse arm at the free end of said gripper, adapted to support a web passing thereover, means carried by the lower end of said platen for supporting a roll of web, means for applying tension to said web adjacent the pivotal support of said gripper, means for swinging said gripper on its pivot, relatively to said platen, a web strap fixed to said platen between said gripper pivot and transverse arm, under which the web is adapted to pass and web reeling means carried by the upper portion of said platen.

2. In web feed for printing presses the combination of an oscillating platen, a gripper pivotally mounted at the lower end of said platen, a transverse arm at the free end of said gripper, adapted to support a web passing thereover, means for adjusting said gripper relatively to its pivotal support to vary the distance of said arm from said support, means carried by the lower end of said platen for supporting a roll of web, means for applying tension to said web adjacent the pivotal support of said gripper, means for swinging said gripper on its pivot, relatively to said platen, a web strap fixed to said platen between said gripper pivot and transverse arm, under which the web is adapted to pass and web reeling means carried by the upper portion of said platen.

3. In web feed for printing presses the combination of an oscillating platen, a gripper pivotally mounted at the lower end of said platen, a transverse arm at the free end of said gripper, adapted to support a web passing thereover, means for adjusting said gripper relatively to its pivotal support to vary the distance of said arm from said support, means carried by the lower end of said platen for supporting a roll of web, means for applying tension to said web adjacent the pivotal support of said gripper, means for swinging said gripper on its pivot, relatively to said platen, a web strap fixed to said platen between said gripper pivot and transverse arm, under which the web is adapted to pass, web reeling means carried by the upper portion of said platen and web tension means between the upper end of said platen and said reeling means.

4. In web feed for printing presses the combination of an oscillating platen, a gripper pivotally mounted at the lower end of said platen, a transverse arm at the free end

of said gripper, adapted to support a web passing thereover, means carried by the lower end of said platen for supporting a roll of web, a transverse bar near the gripper pivot, over which the web is adapted to pass, adjustable web tension means on said bar, means for swinging said gripper on its pivot, relatively to said platen, frictionally driven web reeling means carried by the upper portion of said platen and web tension means between the upper end of said platen and said reeling means.

5. In web feed for printing presses the combination of an oscillating platen, a gripper pivotally mounted at the lower end of said platen, a transverse arm at the free end of said gripper, adapted to support a web passing thereover, a source of web supply adjacent the lower end of said platen, means for applying tension to the web as it leaves said source of supply, means for swinging said gripper on its pivot, relatively to said platen and web reeling means carried by the upper portion of said platen.

6. In web feed for printing presses the combination of an oscillating platen, a gripper pivotally mounted at the lower end of said platen, a transverse arm at the free end of said gripper, adapted to support a web passing thereover, means for adjusting said gripper relatively to its pivotal support to vary the distance of said arm from said support, a source of web supply adjacent the lower end of said platen, means for applying tension to the web as it leaves said source of supply, means for swinging said gripper on its pivot, relatively to said platen and frictionally driven web reeling means carried by the upper portion of said platen.

7. In web feed for printing presses the combination of an oscillating platen, a gripper pivotally mounted at the lower end of said platen, a transverse arm at the free end of said gripper, adapted to support a web passing thereover, means for adjusting said gripper relatively to its pivotal support to vary the distance of said arm from said support, a source of web supply adjacent the lower end of said platen, means for applying tension to the web as it leaves said source of supply, means for swinging said gripper on its pivot, relatively to said platen, web reeling means carried by the upper portion of said platen and web tension means between the upper end of said platen and said reeling means.

8. In web feed for printing presses the combination of an oscillating platen, a carriage mounted for movement transversely of said platen, a gripper pivotally mounted at the lower end of said carriage, a transverse arm at the free end of said gripper, adapted to support a web passing thereover, means carried by the lower end of said carriage for supporting a roll of web, means for applying

tension to said web adjacent the pivotal support of said gripper, means for swinging said gripper on its pivot, relatively to said carriage, said gripper swinging means being operative in one transverse position of said carriage and inoperative in another transverse position thereof and web reeling means

carried by the upper portion of said carriage.

In witness whereof, we hereby affix our ¹⁰ signatures this 3rd day of June, 1926.
